UNITED STATES PATENT OFFICE.

CARL GABRIELSON, OF SYRACUSE, NEW YORK, ASSIGNOR TO L. C. SMITH AND BROS.
TYPEWRITER COMPANY, OF SYRACUSE, NEW YORK, A CORPORATION OF NEW YORK.

TYPE-WRITING MACHINE.

1,018,968.

Specification of Letters Patent. Patented Feb. 27, 1912.

Application filed April 27, 1904. Serial No. 205,203.

To all whom it may concern:

Be it known that I, CARL GABRIELSON, a citizen of the United States, residing at Syracuse, county of Onondaga, and State of New York, have invented certain new and useful Improvements in Type-Writing Machines, of which the following is a specification.

This invention relates to typewriting machines and it comprises especially a type-bar segment which is shiftable to move the type-bars for printing either upper or lower case, means for supporting and guiding the segment, means for shifting the segment and a type guide connected to and movable with the segment.

The invention also comprises other details of construction which will be hereinafter pointed out.

20 In the accompanying drawing, which forms part of this specification, Figure 1 is a front view of so much of a typewriting machine as is necessary to illustrate the present invention; Fig. 1^a is a detail of part 25 of Fig. 1; Fig. 2 is a rear view looking from the line A—A of Fig. 4; Fig. 3 is a plan view of the shift keys; Fig. 4 is a vertical sectional view about on the line B—B of Fig. 1; Fig. 4^a is a plan of the type-guide 30 shown in Fig. 4; and Figs. 5 and 6 are side elevations illustrating in two positions the mechanism for shifting the type-bar support or segment.

Referring to the drawings, 20 indicates 35 the frame of the machine and 21 the platen. The type-bars 22 are mounted upon a segment 23, as illustrated in Figs. 1 and 4, being pivoted to hangers 24 which are removably secured to the segment. These 40 type-bars are arranged to strike rearwardly and upwardly, producing impressions upon the front of the platen where they are clearly visible to the operator. Each type-bar is provided with an ear or projection 29 to which its operating link 30 is pivotally connected. The links 30 are preferably U-shaped in cross section and are constructed of spring sheet metal and provided with ears which embrace the projection 29. The 45 hangers 24 are provided with elongated

openings 41 which render them adjustable toward and from the printing point, to facilitate the alinement of the type. The hangers are connected to the segment 23 by suitable screws 42.

55 As shown in Fig. 4, the type-bars are operated by key levers 43 having keys 44 arranged at the front of the machine in the usual manner. The key levers 43 rock sub-levers 45, the key levers being provided with 60 curved cam slots 46 in which are arranged antifriction rollers 47 mounted on the lower ends of the sub-levers. The sub-levers are suitably pivoted upon a bar 48 and their upper ends are connected with the type-bars 65 by the links 30 previously described. When a key lever is depressed the upper end of the sub-lever is rocked rearward carrying the free end of the type-bar to the printing point on the platen 21. The keys are provided with curved bearing notches 49 which coöperate with the curved bearing on the lower edge of a transverse bearing bar 50, the key levers being held against the bar by springs 51. The springs 51 connect the key 70 levers with adjusting screws 52. These screws are provided with threads of slightly greater pitch than the springs when the latter are not under tension. The screws therefore engage the springs with sufficient 75 friction to prevent slipping and the tension of the springs may be regulated by turning the screws. The screws are mounted in a transverse bar 53. The keys work in combs 54, 55 which hold them in proper relation to 80 each other and guide them vertically. The key levers and type-bars and their intermediate connections are held in their normal positions, as illustrated in Fig. 4, by the springs 51. When in normal position the 85 free ends of the type-bars rest upon a curved pad or support 56.

As the type-bars are necessarily arranged more closely together than the key levers, the sub-levers are preferably arranged in 90 fan-shape as illustrated in Fig. 2 in which the sub-levers 45 of Fig. 4 are shown in rear elevation.

The segment 23 has supporting legs or extensions 71 which are pivotally connected 100

with arms 72 upon a rock shaft 73. (Figs. 1, 3, 4, 5 and 6). The rock shaft 73 has at its left end an arm 74 carrying an antifriction roller 75. The arm 74 has some resiliency, for a purpose to be presently explained. A key lever 76 is provided for temporarily raising the segment 23 when it is desired to write a single capital or figure and a second key lever 77 is provided for 10 raising the segment and holding it in raised position to write, for instance, a line of capitals. The key lever 76 is connected by a pin-and-slot connection 78 with an elbow lever 79 having a cam shaped end 80 located under the roller 75. When the key lever is depressed the upper arm of lever 79 is thrown forward and its cam surface 80 operating on roller 75 rocks the shaft 73 and raises the segment 23 the desired distance.

20 The key lever 77 is connected by a pin-and-slot connection 81 with an elbow lever 82 having in the end of its upright arm a circular notch or depression 83 adapted to receive the roller 75. When the lever 77 is depressed, as shown in Fig. 5, the forward horn of the notch 83 raises the roller 75 a little beyond the point at which the segment reaches its uppermost limit, the spring arm 74 yielding for this purpose. On continuing 30 the depression of key lever 77 the roller 75 drops into the notch 83 and locks the key lever down and the segment up. The elbow lever 82 has a third arm 84 carrying a roller 85 which rises to a position just under key 35 lever 76 when the segment is locked up as shown in Fig. 5. The segment may be unlocked and permitted to fall by depressing key lever 76 upon roller 85, thus rocking the upright arm or lever 82 rearward. The normal 40 position of both levers 79 and 82 is shown in Fig. 4, while the segment is shown locked in uppermost position in Fig. 5, and held temporarily in its upper position in Fig. 6.

45 The levers 76, 77, may be mounted like the other key levers upon the pivot bar 50, and provided with springs 51. The elbow levers 79 and 82 are mounted upon a bracket 86 which is sustained from the main frame by screws 50 87. The screws 87 pass through hollow screws 88 threaded into the main frame and the bracket is drawn tightly against the hollow screws by the screws 87. By loosening the screws 87, the screws 88 may be raised or 55 lowered to adjust the height of the bracket 86, which should then be fastened tightly in place by the screws 87.

The segment is provided at each end with ball-bearings to permit it to rise and fall 60 freely, as shown in Figs. 1 and 1^a. A bracket 89 is provided at each end of the machine to support and guide the segment. A cylindrical opening is formed in a boss 90 of each bracket and in this opening is a

block 91 having in its inner end a V-shaped 65 groove or ball-race. Block 91 is shown as held in position by a screw 92 bearing upon a flattened portion of the block. The brackets 89 also carry vertically adjustable stops 93 which limit the downward movement of 70 the segment 23. At the ends of the segment are angularly adjustable ball-races 94 in which single balls 95 run. Connected with the frame of the machine are adjustable stops 96 which limit the upward movement 75 of the segment. As shown, the ball-races 94 are formed in T-shaped pieces 103 suitably secured to the segment. The balls 95 are retained by the walls of the boss 90, which close the ends of the ball races in block 91, 80 while the ball races 94 prevent escape of the balls laterally. In this simple manner ball retainers are dispensed with. A spring 120 may be used to partially counterbalance the segment 23 if desired. It will be noted that 85 the segment is capable of a slight lateral adjustment by virtue of the adjusting screws 92 of the ball bearings and the adjustable bearings 71^a in the legs 71. This feature is of considerable importance as it permits of accurate adjustment of the segment with reference to the type guide.

The machine is provided with a type guide 97 adapted to accurately direct each type to the printing point. It is important 95 that this type guide should move with the type segment in order that the guide may coöperate at all times with the same part of each type-bar. To accomplish this the type guide 97 (Figs. 1, 4 and 4^a) is carried by a 100 slide 98 which has ball-races in its edges and which runs on three ball-bearings 99, two on one side and one on the other. The three balls are held in place by a retainer 100 having openings to receive them and they run in 105 grooves or races in guide pieces 101. The slide 98 is connected with the segment 23 by a link 102. Centrally arranged under the type guide is an index 104 which coöperates with a scale 105 on the typewriter carriage 110 to indicate the position of the carriage.

It will be understood that the foregoing drawings and description relate to these parts of a typewriting machine which form the subject-matter of the present invention. 115 The complete machine will, of course, be provided with the usual carriage and means for feeding the same to space for letters and words and means for line spacing. The present invention relates only to the mechanism for operating the type-bars, for shifting the type-bars to print upper and lower case and for guiding the type to the printing point.

Having described my invention what I 125 claim and desire to secure by Letters Patent is,

1. The combination with the frame, of an

- upwardly shifting and laterally adjustable segment and laterally adjustable guides for guiding the segment in its shifting movements.
5. 2. In a typewriting machine, the combination with the frame, of an upwardly shifting and laterally adjustable segment, brackets connected to the frame, and guides supported by the brackets for guiding the segment in its up and down movements, said guides being horizontally adjustable.
10. 3. In a typewriting machine, the combination with the frame, of an up and down shifting segment, and angularly adjustable guides for said segment.
15. 4. In a typewriting machine, the combination with the frame and an up and down shifting segment, of pairs of ball-races forming guides for said segment, and balls 20 in said races, one race of each pair being angularly adjustable.
25. 5. In a typewriting machine, the combination with an upwardly movable segment, a rock shaft having an arm connected to said segment, a spring arm connected to the rock shaft, means for operating said spring arm to move the segment and means co-operating with the spring arm to lock the segment in its upper position.
30. 6. In a typewriting machine, the combination of a movable segment, a rock shaft having an arm connected to said segment, a spring arm on said rock shaft, and a cam lever operating on said spring arm to shift 35 the segment.
7. In a typewriting machine, the combination of a movable segment, a rock shaft having an arm connected to said segment, a spring arm on said rock shaft, and a pair of 40 levers arranged to operate on said spring arm to shift the segment, one of said levers being arranged to interlock with the spring arm to prevent the return of said segment.
45. 8. In a typewriting machine, the combination of a movable segment, a rock shaft connected to operate said segment; an arm on said rock shaft, and a pair of levers arranged to operate on said arm to shift the segment, one of said levers being arranged 50 to interlock with the arm to prevent the return of said segment.
55. 9. In a typewriting machine, the combination with a shifting segment, of a rock shaft having an arm connected to said segment, a second arm on said rock shaft, levers operating to rock said shaft, and keys for operating said levers, one of said levers being constructed to interlock with said second arm to prevent return of the segment.
60. 10. In a typewriting machine, the combination with a shifting segment, of a rock shaft having an arm connected to said segment, levers 79, 82, operating to rock said shaft, an adjustable bracket upon which said levers are pivotally mounted, and keys 65 for operating said levers.
11. In a typewriting machine, the combination with a shifting segment, of a rock shaft having an arm connected to said segment, a spring arm on said rock shaft having a pin or roller at its outer end, and a pair of levers 79, 82, co-operating with said pin or roller, each of said levers having a cam surface for raising the pin or roller and one of the levers having a notch adjacent to 75 the cam surface in which the pin or roller may rest to prevent return of the segment.
12. In a typewriting machine, the combination with the key levers, of coiled springs for sustaining the levers in normal position, and adjusting screws entering and engaging said springs, said screws having a pitch slightly greater than the pitch of the springs when the latter are not under tension, for the purpose described.
13. In a typewriting machine, the combination with a shifting segment, of blocks 91 having ball races therein, and holders for said blocks adapted to close the ends of the ball races to prevent escape of the balls.
14. In a typewriting machine, the combination with the segment, of a bearing therefor comprising two ball races and an intermediate ball, a laterally adjustable block in which one of said races is formed, and a 95 cylindrical holder for said block adapted to close the ends of the ball races therein, for the purpose set forth.
15. In a typewriting machine, a sliding type bar segment and guides therefor, in 100 combination with a type guide, and means for adjusting the segment relatively to the guide.
16. In a typewriting machine, the combination with the type guide, of a slidable 105 shifting segment and guides therefor, and means for adjusting the segment laterally and relatively to the type guide.
17. In a typewriting machine, the combination with a slidable type bar segment 110 having ball races, of ball bearings therefor, and means for adjusting said bearings to shift the segment laterally.
18. In a typewriting machine, the combination of a movable segment, a rock shaft 115 connected to said segment, a spring arm connected with said shaft and adapted to rock the same to raise the segment; two levers each adapted to co-operate with said arm to shift the segment, said arm being 120 adapted to move upwardly beyond the position assumed when the segment reaches its upper limit, and means for locking the segment in such position.
19. In a typewriting machine, the combination with a shifting segment, a rock shaft connected with said segment, an arm on said rock shaft, two levers adapted to co-

operate with said arm to raise the segment, |
said arm being adapted to be moved above |
the position assumed when the segment is |
in its upper position when actuated by one |
5 of said levers, and means connected with one |
of said levers for engaging said arm and |
holding the segment in its upper position.

In testimony whereof I have signed my
name to this specification in the presence of
two subscribing witnesses.

CARL GABRIELSON.
